UNITED STATES PATENT OFFICE.

WELLINGTON CROSS, OF FULTONVILLE, NEW YORK.

INSOLE.

SPECIFICATION forming part of Letters Patent No. 466,297, dated December 29, 1891.

Application filed October 15, 1891. Serial No. 408,777. (No model.)

To all whom it may concern:

Be it known that I, WELLINGTON CROSS, of Fultonville, in the county of Montgomery and State of New York, have invented an Improved Article of Supplemental or Inner Sole to be Worn in Connection with Rubber Boots and Shoes; and I do hereby declare that the following is a full, clear, and exact description of the same, reference being had to the accompanying drawings, forming part of this specification.

As is well known to those familiar with the manufacture of and trade in overshoes, such shoes are almost wholly made now of either rubber, or cloth and rubber combined, and are mainly of two fashions as to their shapes—viz., those fashioned or shaped with what are usually designated “sunken heels” and those made without any heel projection—*i. e.*, after the fashion of an infant’s shoe or heelless slipper.

As rubber shoes of the sunken-heel species are especially designed for use over the ordinary leather boot or shoe, and are not well adapted for use over the stocking foot, while overshoes made without any material downward projection at the heel, though not so well adapted to be worn over the usual heeled leather shoe or boot, can be very comfortably worn over the stocking foot, it follows, as a necessity, that the shoe-dealer must carry a complete assortment of each of the two species of overshoes alluded to, in order that purchasers may be suited, as their wishes demand, with either a rubber or cloth and rubber foot-covering that is well adapted to be worn only over the usual heeled leather boot or shoe, or a rubber shoe that can be worn comfortably over the stocking foot, though not so well adapted as the sunken-heel rubber shoe for use over the ordinary leather foot-wear.

As is also well known to overshoe manufacturers and dealers, a rubber overshoe is made and sold to some extent which is formed with a solid heel, after the fashion of an ordinary high-heeled leather shoe, such solid-heel rubber foot-wear being especially designed for use over a foot covered either with what is known to the trade as a “felt boot,” (*i. e.*, a sort of stocking-like article made of felt,) or with a German sock or other stocking.

It is a well-known fact that the article of a false or supplemental sole composed, usually, of a thin layer of cork or other suitable material covered over with or jacketed by an envelope of cloth, flannel, or other suitable fabric and adapted to be slipped within a shoe or boot is manufactured and used in large quantities; such supplemental soles (usually called, I believe, “insoles”) being used mostly in connection with overshoes to better adapt them for use comfortably over the merely stocking foot. Such insoles cannot, however, be used successfully in connection with that species of overshoe made with the sunken heel, since at the vicinity of the heel-socket or interior heel-cavity of the sole no support is afforded by such overshoe to either the heel end or portion of the insole, nor to the heel of the merely stocking foot of the person who may attempt to use the sunken-heel rubber or overshoe without first pulling on a high-heeled leather or under shoe. Hence it will be seen quite a desideratum would be attained to were some simple, economic, and at the same time perfectly efficient means provided by which the wearers of sunken-heel overshoes could utilize their overshoes for wear with perfect comfort over the merely stocking foot. To provide for, use the means by which this desirable end may be attained is the object of my invention, which to this end and object may be said to consist in the improved article, of a heeled insole or a supplemental sole designed (like the ordinary insole) to be worn inside of a boot or shoe, but formed or provided with a heel projection adapted to fill up the heel-cavity of a sunken-heel overshoe, and when placed within such an overshoe make it fit for use with perfect comfort in connection with the merely stocking foot.

To enable those skilled in the art to perfectly understand and practice my invention, I will now proceed to more fully describe it, referring by letters to the accompanying drawings, which form part of this specification, and in which I have shown my improvement carried into effect in the precise form in which I have so far practiced it.

In the drawings, Figure 1 is a perspective view of an insole or supplemental overshoe-sole made according to my invention, Fig.

2 is a longitudinal central section of an ordinary sunken-heel-rubber overshoe having applied to or combined with it one of my improved heeled insoles.

5 A is the upper, B the sole, and C the sunken heel, of a quite common style of rubber or combined cloth and rubber overshoe of that species which is made with a heel-cavity for the reception or accommodation of the usual 10 high heel of the ordinary leather boot or shoe over which said overshoe is designed to be worn, and is supposed to properly fit.

D is a supplemental or inner sole, which is made after the fashion of an article of manufacture which is now and has been for many 15 years extensively made and used and known as an "insole," except that it is formed or provided, as shown at e, with a heel-piece or heel-block which corresponds substantially in 20 shape and size exteriorly with the interior form and dimensions of the heel-cavity of the rubber overshoe in connection with which it is designed to be used. As clearly shown at Fig. 2, this heeled inner sole or insole, when 25 placed within the shoe, rests upon or fits over the sole B thereof, with its heel-block e fitting loosely within the heel-cavity of the shoe, all in such manner that when the thus combined overshoe and heeled insole are worn upon the 30 merely stocking foot of the person, the sole of the foot will be as fully and comfortably supported as if the overshoe alone were worn over the booted foot, while the overshoe will fit to the stocking foot almost as well as it 35 would fit without the heeled insole to the booted or shod foot of the person, since the said heeled insole, it will be seen, practically fills up that space within the overshoe, which, when the latter is worn over the shod foot, is 40 occupied by the heeled sole of the leather boot or shoe.

It is proposed, of course, to supply the market or trade with the heeled insoles of different sizes adapted to fit the various sizes and styles of sunken-heel overshoes, and it will 45 be understood that, with my improved insole on the market, purchasers of that species of overshoes just alluded to can, by a trifling additional outlay for the heeled insoles, provide 50 themselves with the means for utilizing the overshoes for wear on the stocking-clad feet with perfect comfort, and thus gain great comfort and convenience at a very trifling cost.

To a very numerous class of overshoe-wearers who use the sunken-heel rubber shoes, 55 but who have heretofore been unable to wear such overshoes without always first putting on their leather boots or shoes, my invention will fill a long-felt want, since by the purchase of the heeled insoles at a trifling expense (at a cost slightly greater than that of the ordinary insoles used now only in boots and shoes having no heel-cavities) they can often with great advantage to themselves 60 wear out the rubber shoes without putting on any leather or under shoes.

Having now so fully explained my invention that those skilled in the art can make my improved article, and any one can use it, what I claim as new, and desire to secure by Letters Patent, is—

As an improved article of manufacture, a heeled insole adapted for use in connection with a sunken-heel overshoe, as and for the purpose set forth.

In witness whereof I have hereunto set my hand this 8th day of October, 1891.

WELLINGTON CROSS.

In presence of—

T. A. SIMPSON,
J. A. CROSS.
